CLAIM

The ornamental design for a combined bottle and cap, as shown and described.

DESCRIPTION

FIG. 1 is a front elevational view of a combined bottle and cap showing my new design;

FIG. 2 is a top view thereof; and,

FIG. 3 is a front perspective view thereof.

The portions of the combined bottle and cap which are not shown in the drawings or which are shown in broken lines, do not form part of the claimed design.

1 Claim, 1 Drawing SheetFIG. 1.

FIG. 2.
